UNITED STATES PATENT OFFICE.

HARLOW R. FOSTER, OF ASHBY, MASSACHUSETTS.

INCUBATOR.

SPECIFICATION forming part of Letters Patent No. 595,381, dated December 14, 1897.

Application filed March 26, 1897. Serial No. 629,427. (No model.)

To all whom it may concern:

Be it known that I, HARLOW R. FOSTER, of Ashby, in the county of Middlesex and State of Massachusetts, have invented certain new and useful Improvements in Incubators; and I do hereby declare the following to be a full, clear, and exact description of the invention, such as will enable others skilled in the art to which it appertains to make and use the same.

10 This invention relates to incubators and is designed also to be converted into or used for brooders.

The invention consists, essentially, of a water-tank or boiler superimposed over an egg-chamber and having extending therethrough longitudinally a flue leading from a lamp or other caloric-generator.

The invention further consists of a conical deflector movably arranged over the lamp or caloric-generator, which is adapted to be shifted by automatic means from communication with the flue extending longitudinally through the boiler to a second flue or vent leading directly out to the atmosphere.

25 The object of the invention is to maintain at all times a uniform degree of temperature within the egg-chamber or the brooder, controlled by automatic mechanism, which will be hereinafter more fully set forth, and pointed out in the claims.

In the drawings, Figure 1 is a central longitudinal vertical section of a brooder embodying my improvements. Fig. 2 is a transverse vertical section on the line $x-x$ of Fig. 35 1. Fig. 3 is a detail perspective view of the deflector and its attachments.

In the drawings like numerals of reference are used to represent the same parts of construction in the several views.

40 The numeral 1 represents the case or outer framework of the incubator, constructed of any suitable material and form. In the lower portion thereof and preferably extending through the longitudinal length of the same is an egg-chamber 2, which is adapted to be supplied with a series of egg trays or supports of any suitable construction or well-known form, but preferably removable in order that the said egg-chamber may be readily converted into a brooder. This chamber is provided with a door 3 of preferred construction and having thereon suitable fastening means.

At one end of the chamber 2 is an opening 4 to receive a plate of glass to light the chamber 2 and located at that end of the incubator adjacent to the heating-chamber 5. The interior construction of the egg-chamber or brooder, as the case may be, may be made to conform to all the modern features of this class of devices, and, if desired, the egg supports or trays may be arranged in tiers or in any other manner, as may be found necessary to adapt it for the purpose.

55 The heating-chamber 5 is sufficiently large to permit of the placing therein of a lamp or other caloric-generator, and one end of the boiler slightly projects over said chamber to accomplish the desired operation of the several parts of the mechanism, as will be more fully hereinafter set forth. Over the top of 60 the lamp or caloric-generator is mounted a movable deflector 6, which is preferably in the form of a frustum or of a quadrangular pyramid and hollow and having depending from two opposite sides thereof supports or arms 65 7, bent at an angle and their lower portions removably fitted or journaled in opposite sides of the outer casing or frame. Secured to this deflector is the projecting arm or end 7' of a thermostat that is in the main situated in the 70 egg-chamber and the operation of which will be readily understood, and it is intended that any preferred form of thermostat is to be used. When the heat reaches a temperature above that required, the arm of the thermostat 75 will move in the direction to disconnect the deflector in such manner as to convey the heat from the interior to the exterior portion of the incubator until the desired temperature is reached, and should it go below the predetermined point of said arm the thermostat 80 will again move in the opposite direction to cause the heat to flow into the incubator and sustain the requisite temperature. Any of the well-known forms of thermostats will be 85 applicable for this purpose.

90 Above the egg-chamber is a boiler or water-tank 8, having one end thereof projecting over a portion of the heating-chamber 5. In the central portion of the bottom of said boiler or water-tank is a longitudinally-disposed flue 9, which opens through its bottom at one end, as at 10, in order that communication may be had with the deflector hereinbefore set forth,

while at the opposite end the said flue has a smoke-pipe 11 connected therewith and extending upwardly to and above the top of the casing or frame 1 of the device. On the end of 5 the boiler or water-tank which projects over the heating-chamber 5 is secured a flue 12, which is vertically disposed and communicates with the outer atmosphere. The lower part of this flue 12 at its inner side is provided 10 with a depending lip or guard-flange 13, which depends from the upper part of the deflector and limits the movement of the latter to such an extent that when the thermostat operates to change the position of said deflector the 15 latter will be caused to aline itself with the said flue 12 or with the longitudinally-disposed flue 9 in the boiler or water-tank 8.

The operation of the incubator as herein described is simple, as will be readily seen. 20 Normally the deflector 6 will be arranged to communicate with the opening 10 leading into the flue 9 in the boiler 8, it being understood that water is placed in said boiler or tank 8. The water is heated by the caloric passing 25 through the deflector in the flue, and the heat is evenly distributed not only by radiation from the said flue 9, but also by the heated water within the boiler or tank. Primarily the thermostat will be arranged or set to 30 maintain a required degree of temperature within the egg-chamber, but as the temperature in the said chamber exceeds the necessary degree the said thermostat will operate to move the deflector, so that the latter will 35 communicate with the flue 12 until the specific degree of temperature is again reached in the said chamber, when the deflector will move back and communicate with the flue 9. Thus it will be seen that an even distribution 40 and regular temperature will be maintained within the egg-chamber without the attention of an operator. The amount of water placed within the boiler or tank 8 will be varied to suit different kinds of work required 45 to be performed by the incubator, but under all conditions economy in the distribution of heat ensues, as well as saving in the amount of fuel necessary to produce said heat.

It will be understood that many minor 50 details of construction and arrangement of parts hereinbefore mentioned may be changed within the scope of equivalency and be substituted for those shown and described without in the least departing from the nature or 55 spirit of the invention.

It will be seen that the longitudinal flue 9 is connected to and forms a part of the bottom or inner side of the boiler 8, and this feature is very important not only in the operation of the device as an entirety, but also in 60 the convenience which ensues in the construction of the several parts, as the boiler can be quickly arranged for operation in view of the fact that mounting the boiler in place simultaneously positions the flue without further manipulation. The flue can also be arranged to have its end or ends come through the end of the boiler or in any other manner desired so long as the flue preserves its identity within the scope of the invention. 70

Having thus described the invention, what is claimed as new is—

1. An incubator comprising a lower chamber and a superimposed heating-tank or boiler, having a longitudinally-disposed flue in the 75 boiler or tank and a vertical flue at one end of said boiler or tank, an automatically-movable tubular deflector having depending pivoted arms adapted to communicate with said flues in alternation, and a thermostat for operating said deflector substantially as described.

2. In an incubator, the combination with a boiler or tank having a longitudinally-disposed flue therein provided with a smoke-exit 85 at one end and a lower opening at the opposite end, of a vertical flue located at the end of the said boiler or tank adjacent to the said lower opening having a lip or guard-flange depending from the inner lower side thereof, 90 an automatically-operating tubular deflector adapted to communicate with said opening in the flue in the boiler and also with the said vertical flue and having a pair of depending arms with the lower portions thereof journaled in opposite sides of the casing of the incubator, the said deflector being in the form of a frustum of a quadrangular pyramid, and into the upper end thereof projects the lip of the said vertical flue, and a thermostat for 100 operating said deflector, substantially as described.

In testimony whereof I have signed this specification in the presence of two subscribing witnesses.

HARLOW R. FOSTER.
